UNITED STATES PATENT OFFICE.

MILLER REESE HUTCHISON, OF SUMMIT, NEW JERSEY, ASSIGNOR TO LOVELL-McCONNELL MANUFACTURING COMPANY, A CORPORATION OF NEW JERSEY.

MECHANICALLY-ACTUATED DIAPHRAGM-HORN.

1,169,721.

Specification of Letters Patent. Patented Jan. 25, 1916.

Application filed October 25, 1909. Serial No. 524,558.

To all whom it may concern:

Be it known that I, MILLER REESE HUTCHISON, a citizen of the United States, and a resident of Summit, in the county of Union and State of New Jersey, have invented certain new and useful Improvements in Mechanically-Actuated Diaphragm-Horns, of which the following is a specification.

My present invention relates to horns of the above type, particularly such as are contemplated by my prior Patents No. 923,048, 923,049, and 923,122, and various other patents and applications co-pending therewith (see, for instance, application Serial No. 15 494,120 filed May 5th, 1909, Patent No. 1,160,900 granted November 16th, 1915, and Patent No. 1,160,899 granted November 16th, 1915, on a division thereof). In said patents, I have disclosed how a thin flexible 20 steel diaphragm having a fairly definite natural frequency may be caused to produce a note by continuous bodily swing on both sides of normal with a cam push for every swing at frequencies depending on the 25 characteristics of the diaphragm; and also how very fine results may be achieved when only the outermost portions of the cam projections engage the diaphragm when in its rest position. In said prior applications, I 30 contemplated the use of driving means giving any required amount of power and any speed of cam which might be necessary for such method of operation.

My present invention depends upon the 35 discovery that it is possible to embody in a compact, and preferably symmetrical case, a simple driving mechanism of such ratio of speed multiplication that the desired note even at frequencies as high as 300 to 450 40 vibrations per second can be produced by a cam operated mechanism in which the cam may have a sufficient number of teeth, occupying sufficient peripheral space so as not to be of unduly high pitch and in which the 45 multiplying gear may consist of a large gear of diameter approximately that of the diaphragm, while the pinion may have a sufficient number of teeth of sufficient size, and yet the speed and frequency ratios of the 50 above mentioned parts will permit of the desired note when the crank or handle is rotated at speeds not exceeding those which are practicable and convenient for an ordinary unskilled operator. Moreover, 55 the gear ratios are such that the power re-

ducing effect, necessarily attendant upon the speed multiplying effect, is not so serious but that the cam can be forced past the wearpiece from a state of rest without making the range of movement of the crank or 60 other manually operable member of inconveniently great extent. Any difficulty in this respect can be taken care of in any given case by careful adjustment of the degree of overlap of the cam projections with respect to 65 the normal rest position of the diaphragm, suitable provisions for which are described hereinafter.

With the above specific commercially desirable possibilities in view, I have devised 70 novel features including certain combinations and elements which are capable of use in specifically different relations or in connection with coöperating parts specifically different from those set forth herein.

One feature of my invention relates to organization of parts whereby a drive shaft is arranged perpendicularly to the diaphragm, and preferably centrally with respect thereto so that the exterior case may be 80 approximately symmetrical with respect to such shaft as an axis. One advantage of such an arrangement of the shaft is that a crown gear mounted directly on the drive shaft may be used to operate a pinion mounted directly on a cam shaft, preferably at right angles to said drive shaft and parallel with the diaphragm. I prefer to dish the crown gear on the side toward the diaphragm. In this way I provide clearance 85 space, permitting use of a rotary cam of much greater diameter than the diameter of the pinion, the advantage being that this makes possible the combination of a pinion having great ratio of multiplication, with a 90 cam driven directly thereby having a large number of teeth, and at the same time the cam shaft may be arranged approximately parallel to the diaphragm. The end wall 95 of the case may be dished to correspond to 100 the dishing of the large gear, thereby affording an ample clearance for the crank or handle.

Another feature of my invention depends upon the discovery that the necessary relative adjustment of the degree of overlap of the cam and diaphragm wearpiece, which for the best results must be extremely fine and accurate, may be effected in a simple and inexpensive way by an adjustment of 110

the diaphragm with respect to the cam, while maintaining the axis of the cam fixed. This greatly simplifies the apparatus and the expense thereof. The expedient which I employ involves a use of cushioning gaskets of material having the qualities of cork, arranged on both faces of the diaphragm adjacent to the edges thereof, between it and the clamping faces of the main and front members of the case. The adjustment is effected by making the clamp massive and rigid and providing heavy screws or bolts whereby they may be held in clamping relation under considerable stress. The adjustment is effected by forcing the front clamping member toward the member carrying the cam shaft, thereby compressing the gaskets and forcing the diaphragm toward the cam a distance equal to the amount of compression of the gasket.

A horn of the above construction is simple, compact, easily assembled and disassembled, manually operable, has its operative parts so arranged as to permit of the ready adjustment thereof, and will produce a very loud note of desirable pitch.

The accompanying drawings illustrate one form of horn embodying my present improvements, although it will be understood that the scope of said improvements is only limited by the claims hereinafter presented.

Referring now to the said drawings in which like reference characters have been used to designate like parts in the several views—Figure 1 is a side elevation of one form of a manually operable horn, partly broken away to vertical longitudinal section, Fig. 2 is a front elevation of the said horn with the diaphragm and horn removed, Fig. 3 is a rear elevation of the horn proper with the diaphragm and diaphragm-engaging washers in position, some of the parts being shown in dotted lines, Fig. 4 is a detail view of the cam shaft, partly in elevation and partly in section, showing a portion of the shaft and cam lubricating means embodied in said shaft, and Fig. 5 is a plan view of a cam suitable for use in a manually operated horn.

In Fig. 1 the device is shown as mounted upon a base 1, which is provided with screw holes 2 for securing it to a vehicle or other platform. This base is intended to be mounted firmly in position and in order that no particular pains should be necessarily used in positioning the same, the horn is made rotatively adjustable thereon. To this end the upper portion of the base is socketed as at 3, and provided with a thumb nut or a like device 4, threaded thereinto through a boss upon the base and adapted to engage a groove 5 in the spindle 6. This construction permits of rotative adjustment of the horn, but further allows of the horn and mechanism therefor being wholly removed

from the socket if it be so desired, the withdrawal of the thumb nut from engagement with the groove permitting the removal of the horn casing. The spindle 6 extends from and is preferably integral with a casing 7, said casing being substantially cylindrical with flanges 8 and 9 formed respectively on the front and rear ends thereof. In the front flange 8 are spaced threaded apertures 10 for the reception of screws 11. These screws pass through front case plate 12, a front washer 13, diaphragm 14, a rear washer 15, and are threaded into the apertures in the casing flange.

The washers 13 and 15 perform several functions and are preferably made of some compressible cushioning material, which should be of sufficient thickness to cover the desired range of adjustment of the diaphragm as hereinafter described. Cork or composition cork, certain kinds of fibrous material having similar qualities are adapted for this purpose.

Considering the effect of compressing the cushioning washers, when they are of equal thickness, it will be seen that if the screws 11 are of, for example, thirty-two pitch, a single turn of said screws will draw the horn frame inward one-thirtieth of an inch, but the diaphragm will have been pushed in but one-half of this amount, or one-sixty-fourth of an inch. This permits of a very fine adjustment of the said diaphragm with respect to the cam 16, positioned at the rear thereof. By making the horn side washer of greater thickness than the cam side washer, this fineness of adjustment is increased, and vice versa.

If the diaphragm be advanced inwardly too far, the resilience of the cushion upon the inner side thereof will serve to permit of the adjusting screws being withdrawn to some degree without thereby impairing the grip of the washers upon the periphery of the diaphragm. This simple arrangement affords a unique and effective means for relatively adjusting the diaphragm and cam, and is of especial importance because of the ease with which adjustment may be accomplished and because the cam operating parts may be made nonadjustable within the casing, thereby cheapening the cost of manufacture and simplifying the device.

The cam 16 is mounted upon cam shaft 17 which is positioned parallel to the plane of the diaphragm and is journaled in bushing 18, which in turn is carried by brackets 19, the latter being preferably formed integral with the casing 7. The ends of the cam shaft are reduced or turned down, as at 20—21, the end 20 having secured thereupon by suitable means a beveled pinion 22. The upper end 21 of said shaft carries the cam, which is keyed or otherwise secured thereto, as, for example, by a pin 23. A nut 24 is

screwed down upon the threaded portion 25 of the upper end of the said shaft, which in turn is secured by a lock nut 26. The upper end of this lock nut is counterbored or recessed and the end of the cam shaft is also correspondingly counterbored, preferably so as to form a cone-shaped depression 27. A drilled hole 28 leads downward from the cup-shaped depression or reservoir, and another drilled hole 29, extends obliquely outward from the center of the shaft. An oil cup 30 of suitable construction is secured in the casing directly above the recesses before mentioned in such manner that drops of oil may fall downward through the casing into the said cup-shaped depression and so flow on down through passages 28-29 to lubricate the bushing or bearing 18. Some oil will find its way over the sides of the reservoir to the operating peripheral surfaces of the cam by centrifugal force.

The pinion 22 which rotates the cam is driven by a bevel gear 30, which is dished as shown in Fig. 1 at 31. As explained above, this recessing or dishing of the bevel gear permits the use of a relatively large cam. Gear 30 is provided with a spindle or shaft 32, preferably formed integral therewith, said shaft being mounted in a bearing or bushing 33, which is carried in a hub or boss upon the center, or substantially so, of the rear plate 34. This plate is bolted or otherwise secured to flange 9 of the casing, and it will be noted that the removal of these bolts permits the driving mechanism of the horn to be removed without in any manner disturbing the diaphragm; and the cam shaft may be removed from, or replaced into, its bearing without disarranging the nice adjustment of diaphragm with respect to the bearings of the cam shaft.

The construction shown is compact and simple; the shaft 32 is positioned substantially in the axis of the horn and perpendicular or normal to the surface of the diaphragm. The handle 35, carried by the crank 36, which is mounted upon the reduced and threaded end 37 of the said shaft, is hence adapted to be rotated in a plane parallel to that of the diaphragm. This arrangement is desirable; since the handle movement, if in another plane, would be awkward.

Referring now to Figs. 1 and 3, the horn 38 is flared somewhat more along the perpendicular axis thereof than on the horizontal, and is secured to the front of face plate 12 by rivets 39. These rivets are spaced in a particular manner, which corresponds to the spacing of the adjusting screws 11. The respective rivets and adjusting screws are arranged in groups in such fashion that the face plate with the laterally flattened horn secured thereto may be secured to the casings in but two positions, in both of which

the wide span of the horn mouth will be vertical. This locates the horn and diaphragm in one of two possible positions. The wear piece 40 on the diaphragm is adapted for engagement by the cam on two sides only, and the bolt holes in the edge of the diaphragm are so related to the wear piece that the diaphragm will be secured only in one of its two proper positions. This permits the diaphragm to be removed and replaced in reverse position to expose either surface of the wear piece to the cam. A similar disposition of the rivet hole in the base of the horn proper and the flange to which it is secured, insures that the horn will be riveted to the face plate in one of its two proper positions. This obviates the possibility of error through carelessness or inadvertence of workmen when assembling these parts in the course of manufacture.

The preferred form of rivet and bolt spacing, which, however, is only one of many which may be used to accomplish the desired results hereinbefore described, is one in which the securing devices nearest the plane of shortest diameter of the horn are farther from each other than they are from those nearer the plane of the major diameter.

In my present device, as shown in the drawings, I have succeeded in producing a hand operated horn having the same method of operating and producing the same standard full speed note as the motor driven horns of my prior patents first above mentioned. As the drawings show, the rotor has twenty cam teeth and the multiplying gear gives somewhat more than five revolutions of the cam shaft for one revolution of the crank, so that crank speeds somewhere between three and five revolutions per second will give cam contacts at the required rate, which will be somewhere between three hundred (300) and four hundred and fifty (450) or more per second, dependent on the characteristics of the particular diaphragm used. While, as practical tests will show, any operator can conveniently attain such hand crank speed, increase of speed beyond this involves considerable exertion. Moreover, the governing effect of the diaphragm on the cam at such speeds, explained in my prior patents, becomes progressively more powerful in preventing further increase of speed. Hence, with a horn designed for proper operation at the above rate, it will become wholly impractical for the operator to increase his speed to double that rate, and hence, in practice, the cam will never be accelerated to a speed sufficient to intercept and cut short the return swings of the diaphragm at or near the rest position thereof. Thus, the design of the instrument with reference to the physical limitations of the average operator insures that normal full speed operation will produce only the standard

full swing note with a cam push for every swing of the diaphragm; a result attained in my prior devices by employing as the driving means, a suitable friction wheel or a small electric motor, adepted to permit the speed to vary in accordance with the work done upon the diaphragm.

While I have herein fully shown and described, and have pointed out in the appended claims certain novel features of construction, arrangement, and operation which characterize my invention, it will be understood by those skilled in the art that various omissions, substitutions, and changes in the forms, proportions, sizes and details of the device, of the materials used, and of their operation, may be made without departing from my invention.

I claim:

1. A horn or signal having a diaphragm, a member rotatable about an axis normal to said diaphragm at the center of the latter and having teeth on the face thereof toward said diaphragm and spaced circularly with respect to said axis and means arranged between said rotatable member and said diaphragm substantially radially in respect to said axis for operatively engaging said teeth and said diaphragm at the center of the latter and imparting vibrations to said diaphragm upon the rotation of said rotatable member.

2. A horn or signal having a diaphragm, a drive shaft normal thereto, a rotor having face projections and mounted concentric with said shaft and radially disposed means between said rotor and said diaphragm and operatively engaging with said projections and said diaphragm at the center of the latter for imparting vibrations to said diaphragm upon the rotation of said shaft and rotor.

3. A horn or signal having a diaphragm, a rotor movable about an axis normal to said diaphragm at the center of the latter and having an annular row of projections concentric with said axis and a movable member between said rotor and said diaphragm, said movable member receiving movement from said projections and imparting vibration to said diaphragm at the center of the latter upon the rotation of said rotor.

4. A horn or signal having a diaphragm, a rotor movable about an axis normal to said diaphragm and having an annular row of projections concentric with said axis and means for vibrating said diaphragm upon the rotation of said rotor, said means including a movable member disposed between said rotor and said diaphragm and arranged radially in respect to said axis, said movable member having operative engagement with said projections and with said diaphragm.

5. A horn having a diaphragm, a wear piece secured thereto at the center thereof, a rotor movable about an axis normal to said diaphragm and having an annular row of projections concentric with said axis and means for vibrating said diaphragm upon the rotation of said rotor, said means including a movable member disposed between said rotor and said diaphragm and arranged radially in respect to said axis, said movable member having operative engagement with said projections and with said wear piece.

6. In an alarm or signal device, a diaphragm, a rotary member mounted to rotate about an axis substantially parallel to the diaphragm adapted to contact with the latter to vibrate the same, and means for operating the rotary member comprising a power shaft substantially perpendicular to said diaphragm and having its axis substantially in line with the center of said diaphragm.

7. In an alarm or signal device, a diaphragm, means for vibrating the diaphragm comprising a rotary member mounted on a shaft substantially parallel to said diaphragm, and driving means for said rotary member comprising a pinion on the shaft of said rotary member, a power shaft substantially perpendicular to the diaphragm at the center of the latter, a large gear on the power shaft meshing with said pinion and means for supporting said parts in compact forms.

8. In an alarm or signal device, a diaphragm presenting a projection or wear piece at its center, a cylindrical casing in the rear of said diaphragm and of substantially the same diameter as said diaphragm and having its axis normal to the diaphragm at the center of the latter, a shaft supported within said casing and having a head presenting a plurality of teeth for successive engagement with said wear piece to vibrate said diaphragm by forcing said wear piece bodily away from said shaft, a pinion on said shaft, a drive shaft normal to said diaphragm and having a large gear meshing with said pinion and a handle outside of said casing and movable in a plane parallel to said diaphragm for manually rotating said drive shaft.

9. A device of the character specified, comprising a casing having at one end an opening and having a laterally extending flange at the opening, a plate provided with a central nipple registering with the opening, an intensifying horn having one end engaged with the nipple, a diaphragm arranged between the plate and the flange across the opening of the nipple, said diaphragm having a transversely rounded lug on its inner face, a disk mounted to rotate in the casing, said disk having teeth for en-

- gaging the lug to vibrate the diaphragm when the disk is rotated, means for rotating the disk, said means comprising a pinion co-axial with the disk, a gear wheel journaled in the casing and engaging the pinion, and a crank connected to the gear wheel for turning the same.
10. A device of the class specified, comprising a casing having at one end an opening, a plate extending across said opening and provided with a central nipple, a projector having one end engaging with the nipple, a diaphragm arranged between the plate and the end of the casing across the opening, said diaphragm having a wear-piece on its inner face, a disk mounted to rotate in the casing, said disk having teeth for engaging the wear-piece to vibrate the diaphragm when the disk is rotated, means for rotating the disk, said means comprising a pinion co-axial with the disk, a gear-wheel journaled in the casing and engaging the pinion, and power means connected to the gear wheel for turning the same.
15. A horn or signaling device having a diaphragm, a member having its axis normal to said diaphragm and having an annular row of gear teeth concentric with said axis and a member between said first mentioned member and said diaphragm, said second mentioned member including a shaft parallel with the diaphragm, a pinion meshing with said first mentioned member and a cam for vibrating said diaphragm, and means for rotating one of said members in respect to the other and about said axis.
20. A horn or signaling device having a diaphragm, a member having its axis normal to said diaphragm at the center of the latter and having an annular row of gear teeth concentric with said axis and of a diameter approximating that of the diaphragm, and a member between said first mentioned member and said diaphragm, said second mentioned member including a shaft parallel with the diaphragm, a pinion meshing with said first mentioned member and a cam for vibrating said diaphragm, and means for rotating one of said members in respect to the other and about said axis.
25. A horn having a diaphragm, a wear-piece secured thereto at the center, a member having its axis normal to said diaphragm and having an annular row of gear teeth concentric with said axis, a member disposed between said first mentioned member and said diaphragm and including a shaft arranged radially in respect to said axis, a cam engaging with said wear-piece and means for affecting a rotation of said shaft and cam about their axis upon a rotation of one of said members about said first mentioned axis.
30. A horn or signaling device having a diaphragm, a gear wheel of a diameter approximating that of the diaphragm and having its axis normal to the diaphragm and having its teeth presented toward said diaphragm, a shaft between said gear wheel and said diaphragm and substantially parallel to the latter, a rotor carried by said shaft for vibrating said diaphragm, and means for rotating said shaft upon the rotation of said gear wheel.
35. A horn or signaling device having a diaphragm, a diaphragm casing extending rearwardly therefrom and including a peripheral wall clamped to the peripheral portion of said diaphragm and a rear end wall, a shaft projecting through said rear wall and carried thereby substantially at right angles to said diaphragm, a shaft within said casing, journals supported from said peripheral wall and carrying said second mentioned shaft, a cam carried by said second mentioned shaft for vibrating said diaphragm, and gearing for rotating said second mentioned shaft upon the rotation of said first mentioned shaft.
40. In an alarm or signal device, a diaphragm presenting a projection or wear-piece at its center, a cylindrical casing in the rear of said diaphragm and having its axis normal to the diaphragm at the center of the latter, a shaft supported within said casing parallel to said diaphragm and having a head presenting on its periphery a plurality of teeth for successive engagement with said wear-piece to vibrate said diaphragm by forcing said wear-piece bodily away from said shaft, a pinion on said shaft, a drive shaft having a large gear within said casing and meshing with said pinion, and a manually operable member outside of said casing and movable in a plane parallel to said diaphragm for rotating said drive shaft.
45. In an alarm or signaling device of the class described, a thin elastic steel diaphragm provided with a suitable wear-piece, a casing including a front wall carrying a horn or mouth-piece and a rearward extension clamped to said front wall to secure the periphery of the diaphragm therebetween, forming with said diaphragm a closed chamber, and a rotary cam having a multiplicity of cam projections rotatably mounted within said chamber and slightly overlapping said wear-piece, in combination with a manually operated driving mechanism for said cam comprising a manually operable member located outside of said casing and extending into the same, and a speed-changing, power-transmitting mechanism within said casing and operatively connected with said member and said cam for actuating the latter, the number of the projections on said cam, its overlap on the wear-piece and the ratio of its peripheral movement to the movement of the manually operable member being predetermined with reference to each other and

with reference to the characteristics of the diaphragm so that the cam may be easily started and quickly speeded to a full normal speed giving a bodily swing of said diaphragm on both sides of its normal rest position with a cam push for every swing.

Signed at New York city, in the county

and State of New York, this 22nd day of October, A. D., 1909.

MILLER REESE HUTCHISON.
